INSULATED PERISHABLE FOOD CARTON

Donald B. Kauffeld, Lexington, Ky., assignor to Excel-O-Therm Container Corporation, Lexington, Ky., a corporation of Kentucky

Filed Aug. 26, 1957, Ser. No. 680,322

4 Claims. (Cl. 229—3.5)

This invention relates, broadly construed, to an improved mode of packaging perishable food products for unit consumption at the retail level and has reference in particular to an insulated carton in which the construction is such that important matters of sanitation, practical storage and handling, reliable protection of food quality, and satisfactory display and identification factors have not only been taken into account but effectually met.

As will perhaps be evident from the preceding general statement of the nature of the subject matter of the invention, an insulated carton is under consideration wherein hot, cold or frozen products are involved and are kept for a limited time, say during transportation and similar handling steps, without the use of a refrigerant or a heating agent, as the case may be.

Current trends toward widespread adoption and use of insulated food packages and cartons in which the principal package components are aluminum foil laminates have long since been recognized and tested and otherwise experimented with. Such packaging achievements have made it possible for manufacturers to cope with the continuing demands for individual consumer unit packaging and merchandising. Manufacturers and retailers of hot and cold food products advocate the appropriation and use of attractive and eye-catching cartons in this category for a number of reasons; for example, looking toward protection against deleterious effects of light and moisture, hoping to provide a carton having resistance to physical damage and such that it will insure maintenance of the prerequisites of product quality. Identification media, involving colors, styling and provision for trademarks and printed matter, may be incorporated and successfully utilized wherever necessary or required. A desire to keep abreast of efficient packaging needs has been the incentive in the instant matter, looking toward advancing the carton and container art.

More explicitly, the instant concept pertains to a laminated container or carton which is expressly, but not necessarily, designed and adapted to serve as a take-home-type carton for ice cream. As hereinafter revealed, it is my objective to structurally, functionally and otherwise improve on cartons in the stated category in which the package needs and functions are efficaciously satisfied.

Looking toward giving a background and to help to bring the results of the instant development into focus, certain information on package classification is thought to be proper here. Using containers and cartons somewhat synonymously, three general classifications, somewhat arbitrary in definition, are commonly referred to in the trade. That is to say, they are (1) so-called rigid cartons and containers or packages, for example, bottles, cans, jars, and the like. Secondly, a package or container which will support its own weight including the product, and yet which is such that it may be de-formed or

2

collapsed and which may or may not conform precisely to the shape of the product are (2) the so-called semi-rigid types. The principal example would be cartons. Finally, there are the so-called containers which do not support their weight and which collapse, such as bags, over-wraps, loose liners and so on, referred as (3) the flexible package.

The invention under advisement falls in the semi-rigid group and relates, as already stated, to a carton and although the idea involves protecting hot, cold and frozen food products, it will simplify the entire presentation to keep in mind that the principal aspect of the concept is what is to be hereinafter referred to as an ice cream carton.

In packaging ice cream, it is generally conceded that the packaging materials which are selected for commercialization purposes markedly influence quality retention during storage in self-service refrigerating cabinets or wherever heat exchange at room temperature is involved. For the most part, cartons commonly used and which are paraffin coated are customarily referred to as "fibre" cartons. However, and in the course of research and with a view toward retarding shrinkage and protecting and preserving the body texture and keeping qualities of ice cream, many and varied packaging techniques and procedures have been resorted to. In the course of experiments, in comparison with waxed fibre and plastic containers, all-aluminum packages and fibre containers with foil overwraps or laminate exteriors have been found to effectually retard body and texture deterioration and to minimize shrinkage even where ice cream is stored one month at top level open-top and sliding glass top self-service merchandizing cabinets. The value of the exteriorly covered laminate using foil resides in its ability to reflect radiant heat. It has been shown that foil exteriors conduct absorbed heat to lower colder sections of a cabinet where it is dissipated. Some packages and cartons are overwrapped in foil and others have laminated foil interiors and liners and various ways of incorporating insulators have been used and are known.

The objective in the instant case is to utilize a composite sheet material which is formed or fashioned into a carton and wherein the conductive and radiant reflective characteristics or properties of the foil are especially effective in maintaining the lowest expected temperature in ice cream at the top level of a self-service cabinet, where under recognized circumstances heat absorption is usually the greatest.

As will be hereinafter evident, the improved carton revealed has to do with an aluminum laminated container which, in practice, shows that the same taste appeal attending ice cream packed in metal cans in bulk form is had. Interior and exterior surfaces are plastic coated for taste and flavor retention.

Secondly, the containers require less freezing time in the hardening room, create a double freezing action which eliminates ice crystals and dehydration. Protection against heat shock, shrinkage in transportation and handling in self-service cabinets, and undue warm-up has been achieved.

In addition, the containers or cartons devised deflect 82% of heat and light, resulting in effective insulating and maintenance of quality from the store to the home. They insure better keeping qualities in the home refrigerator plus the advantage of a re-usable container for frozen foods.

The above and many other features and advantages will become more readily apparent from the following description, the views of the drawing and the concluding claims.

In the drawing, wherein like numerals are employed to designate like parts throughout the views:

Fig. 1 is a perspective view of an ice cream box, carton or container, constructed in accordance with the principles of the present invention showing the same empty but made and ready for use.

Fig. 2 is a horizontal section on an exaggerated scale, taken on the horizontal line 2-2 of Fig. 1, looking in the direction of the arrows.

Fig. 3 is a further exaggerated view showing the laminates or plies of material bonded together to provide the 3-ply plastic coated sheet material from which all components of the carton are made.

Fig. 4 is a fragmentary perspective view illustrating certain indentations punctured at prerequisite points.

Fig. 5 is an exaggerated section on the line 5-5 of Fig. 4, looking in the direction of the arrows.

As the views of the drawing clearly depict, the ice cream carton as an entity is denoted in Fig. 1, for example, by the numeral 8. Cartons vary in size and shape and weight, and therefore the expression "carton" is being used here to make reference to the whole range and also to so-called packages, containers, boxes, and so on, in the aforementioned semi-rigid category only, of course. For this and other reasons it seems unnecessary to dwell upon what the carton looks like or how it is constructed except that the walls or components are folded, creased and formed and secured together to form a container. Of chief significance, as already mentioned, is the fact that the composite sheet material which is used in providing the component walls, flaps or parts of the container is of chiefest interest here.

The components or walls of the carton are all the same, and consequently the basic material which may be referred to as insulated laminated or sheet material is the same throughout and any portion or section thereof would be of the cross-section seen, for example, in Fig. 3. As an entity, the material is denoted by the numeral 10. It is characterized by an outer or exterior ply or laminate of aluminum foil 12, by a corresponding inner laminate or layer of aluminum foil 14, and an intervening body layer or laminate 16. The latter is of paper stock, more specifically so-called blotter stock. Not only this, it is not standard or "ordinary" blotter stock, but a specially made product which is bulked-up to render it of proper tensile strength and to promote the multiplication of non-communicating air pockets or cells for insulation properties and also to promote the requisite compressibly resilient properties so needed in making it possible to produce a laminated material which may range from 18 points to 32 points and which, consequently, lends itself to folding, creasing and forming into containers. In addition, it lends itself to scoring, die-cutting and to many styles and forms. Consequently, a novel laminated insulated blank is had. Further, it lends itself to printing either on offset or letter press or rotogravure. Even though the dead air cells are compressed during the printing operation, they expand much in the manner that a cushion would do after the printing, and despite this change in the material while being squeezed, it does not affect the intended insulation properties before or after printing. So far as is known, the provision of a body layer 16 having these properties and sandwiched between aluminum foil cover plies is novel, especially wherein the exterior surfaces of the foil plies are coated with commercial plastics or a film of plastic material denoted at 18 and 20, respectively. Thus constructed, the material eliminates precipitation formation on the exterior of the container which would tend to destroy the reflecting property so sorely depended upon. Experiments have shown that after the vinyl polymer coats are applied, tests reveal 0.01 instead of 0.29 having to do with water vapor transmission of thin aluminum foils. Consequently, the sheet material employed is practically moisture proof.

It is also to be noted, particularly in Figs. 4 and 5, that during the course of manufacture and while transforming the material into a box, the inner foil lamination and plastic coating is punctured at 22 to expose a minimal portion 24 of the ply of insulation 16. By way of these punctured portions at prescribed points, particularly where the end flap 26 is bent at 28 and folded over and against the surface 30 of the wall 32, this makes for proper bonding of the surfaces. Bonding plastic to plastic would be extremely difficult. However, by providing exposed portions 24 of the insulation material 26, it can be seen that the adhesive media (not detailed) results in providing a strong bond and resistance to moisture and air leakage.

As indicated earlier, aluminum, foil, when coated with proper plastic media providing a satisfactory film surface, may be printed by any commercial processes used on flexible packaging materials. Taking into account and meeting press and use requirements for displaying advertising is a highly significant factor in turning out proper material for production of an ice cream carton, as is obvious.

Minor variations in carrying the invention into practice which do not depart from the spirit of the concept or properly evaluated scope of the claims may be resorted to in practice.

What is claimed as new is as follows:

1. For use in packaging, storing in refrigeration cabinets, when being transported, and when otherwise handling hot, cold, or frozen food products for unit consumption; a foil-clad semi-rigid carton whose wall portions and component portions are constructed from flexible, foldable laminated sheet material embodying interior and exterior surface-covering thin imperforate aluminum foil laminates and a semi-rigid laminate of insulation material sandwiched between said foil laminates, said foil laminates being spread and flatly superimposed upon and bonded to opposite but respectively adjacent sides of said insulated laminate, the entire inner and outer surfaces and body portion of the latter having a myriad of non-communicating dead air cells, said inner and outer surfaces covered by the foil laminates and providing covered dead air pockets, and said foil laminates having prerequisite conductive and radiant heat reflective properties functioning to maintain the lowest temperature possible when said carton has been stored at upper levels in self-service refrigeration cabinets and the like.

2. The structure defined in claim 1, and wherein said intermediate laminate comprises a prefabricated ply of compressibly resilient blotter stock, the complete sheet material product being produced in thicknesses ranging from 18 points to 32 points, whereby to adapt itself to feasible folding, creasing, scoring, die-cutting and varying printing press and printing requirements without losing its given original form and character.

3. The structure defined in claim 2 and wherein said intermediate laminate is a ply or bulked-up blotter stock and which as a result of the bulking-up process appreciably and materially multiples the number of available and usable dead air cells, promotes compressibility without deviating from body strength necessary to provide the semi-rigid properties needed, and provides the compressibly resilient properties that can and must be relied upon for wide range printing needs.

4. For use in packaging, storing in refrigeration cabinets, when being transported and when otherwise handling hot, cold, or frozen food products for unit consumption; a foil-clad semi-rigid carton whose wall and other carton-forming components are constructed from laminated sheet material embodying interior and exterior surface-covering thin aluminum foil laminates and a single semi-rigid laminate of insulation material sandwiched therebetween, said foil laminates being spread and superimposed upon and bonded to their respective sur-

faces of said insulated laminate, the cooperating bonded surfaces of the several laminates providing a myriad of non-communicating dead air cells, and said foil laminates having prerequisite conductive and radiant heat reflective properties so as to maintain the lowest temperature possible when said carton is stored at upper levels in self-service refrigeration cabinets and the like, said intermediate laminate being characterized by a single ply of compressibly resilient bulked-up blotter stock, the exposed exterior surfaces of the aluminum foil being coated, each with a film of negligible thickness, the vinyl polymer plastics, rendering the surfaces substantially moisture-proof.
